MOBILE FIRE DETECTION AND SUPPRESSION UNIT

Robert E. Benshoof, Covina, Calif., assignor to CBF
Systems, Inc., Covina, Calif.

Filed Jan. 11, 1971, Ser. No. 105,756

Term of patent 14 years

Int. Cl. D12—08

U.S. Cl. D14—3

FIG. 1.

FIG. 2.

FIG. 7.

FIG. 1 is a side elevation of the mobile fire detection and suppression unit with a side rear cover in a raised position.

FIG. 2 is a plan view of the unit as shown in FIG. 1.
FIG. 3 is a side view from the opposite side.

FIG. 4 is a front elevation, and FIG. 5 is a rear elevation of FIG. 1.

FIG. 6 is a view similar to FIG. 1, but with the covers in closed position.

FIG. 7 is a rear elevation of FIG. 6.

I claim:

The ornamental design for mobile fire detection and suppression unit, as shown and described.
